LOOSE-LEAF BINDER

Atto N. Hanna, Atlantic Highlands, N. J.

Application February 24, 1944, Serial No. 523,645

1 Claim. (Cl. 129—9)

1

The invention relates to loose leaf binders and more particularly to a binder of the type having relatively movable plates, each having a number of arcuate posts, each post on one plate complementing one on the other plate to form a continuous loop, upon which loops perforated sheets may be mounted and have free sliding movement from adjacent one binder cover to adjacent the other such cover.

I have heretofore developed and produced binders of the type above referred to, using two plates pivoted together at one end and having arcuate posts which by pivotal movement of the plates in one direction are brought to a position to form a series of substantially continuous closed loops, the plates and loops being locked in the closed position by means carried by the free end of one plate cooperating with means on the free end of the other plate.

While binders of this type have been used in large numbers, when the loops of the binder were open as a result of pivotal movement of the plates and the posts carried thereby, there was a progressively narrowing width of the gap between the ends of the posts from the free ends of the plates towards the pivotal connection between them, making the mounting and removal of sheets upon and from the posts difficult and awkward. At times the posts, when they were being closed, had a tendency to interfere in a manner to prevent a proper meeting and mating of the complementary posts forming loops adjacent the point of pivotal connection between the two plates due to the arc of movement of the movable plate. This was particularly true if there was any material play about the pivot. Even if the ends of the posts of each pair were properly engaged in abutting relation one with the other, stresses transversely and longitudinally of the plates were developed tending to throw the two posts of some of the loops out of alignment sufficiently to interfere with a free run of a sheet from one post to the complementary post. This condition resulted in deflection of some of the posts relative to others and in time, due to such distortion such posts would take a permanent set requiring the use of openings in the sheets to compensate for slight variation in the spacing of the loops towards the pivoted ends of the plates.

One plate in such binders is customarily secured, by riveting, to the back board of a book and when the binder is opened, the leaves upon the posts carried by the movable plate are extended at an oblique angle to the fixed plate,

2

the adjacent back board and the leaves or sheets upon the posts of said fixed plate so as to project beyond the edge of the cover of the book and make mounting and removal of sheets upon the posts of the movable plate awkward beyond that resulting from the progressively narrower gap between the ends of the posts upon the plates towards the pivotal connection between said plates.

10 The binder of my present invention is so constructed that when the two plates carrying complementary arcuate posts, are actuated to open the binder, a gap is formed between the ends of the posts of uniform width as to all posts, this gap being sufficiently wide to permit equally free access to every post in mounting sheets thereon or removing them therefrom. This results from a structure in which one plate is slidably mounted upon the other and retained 15 and guided in its movement thereon in a manner to permit it and its posts to have only a right line movement in relation to the other plate and its posts and to limit the quantity of such movement to that required to space the ends 20 of all posts carried thereby an equal distance from the ends of the complementary posts carried by the other plate, or to produce a gap of substantially uniform width between the ends 25 of all of the posts on one plate and those on 30 the other plate.

At the opposite ends of the plates are manually operative mechanisms capable, during the final closing of the binder, of simultaneously drawing the ends of all complementary posts 35 together and holding them and the plates carrying same against relative movement unless said locking mechanisms are released.

In addition to the means for controlling and 40 limiting the right line movement of the movable plate, and its posts, I provide the fixed plate with a plurality of tongues spaced therefrom sufficiently to overlay the movable plate and prevent any appreciable lifting thereof. Preferably the movable plate is provided with raised 45 stiffening ridges or ribs at least one of which is engageable with these tongues both when the binder loops are opened and when they are closed. The tongues may be of a length to engage all ribs on the movable plate when the 50 binder loops are closed so as to ensure the maximum immobility of the plates and posts while the binder is in use.

The right line movement of the movable plate and its posts in relation to the fixed plate and 55 its posts, ensures a direct, accurate engagement

of the ends of all complementary posts without developing any stresses tending to distort or deflect any of the posts, notwithstanding repeated movements of the movable plate.

The invention consists primarily in a loose leaf binder embodying therein two plates one of which is a fixed plate having a plurality of spaced arcuate posts projecting upwardly from one edge and transversely thereof, and the other of which is slidably mounted upon said fixed plate and has a like number of complementary arcuate posts projecting from one edge upwardly and transversely of the plate towards the posts upon said fixed plate and adapted with right line movement of said movable plate to have their ends engage with the ends of the posts upon said fixed plate to form a series of closed loops, cooperating means upon said plates whereby a limited right line movement of said movable plate and its posts towards and from the posts upon said fixed plate is permitted and releasable means carried by one of said plates and engageable with the other plate whereby when the posts are engaged movement of said movable plate is prevented; and in such other novel features of construction and combination of parts as are hereinafter set forth and described and more particularly pointed out in the claim hereto appended.

Referring to the drawing,

Fig. 1 is a plan view of a binder embodying the invention with the ends of the arcuate posts upon the two plates engaged to form continuous loops;

Fig. 2 is a similar view with the posts disengaged and the movable plate positioned to form a gap between the ends of the posts forming each loop;

Fig. 3 is a side view taken along the line 3—3 of Fig. 2; and

Fig. 4 is a fragmentary view showing a part of the fixed plate, the detailed formation of one of the arcuate posts and one of the overlaying guide tongues, and

Fig. 5 is a detail view of a modified form of guiding, limiting and locking mechanism.

Like numerals refer to like parts throughout the several views of the drawing.

In the embodiment of the invention illustrated by the drawing, the binder embodies therein a plate 10 adapted to be secured in fixed relation to the back of a book binding by means of rivets passing through the openings 11. One book cover is shown at 12 and the other at 13.

Projecting upwardly from one, the outer, edge of the fixed plate 10 are a plurality of spaced, arcuate posts 14, the spacing of such posts varying with the size of the book and the strength required in the binder structure by the weight of the sheets to be mounted thereon. These posts may be spaced apart from about one half an inch to an inch or more apart. The posts 14 adjacent their free ends project across or transversely of the plate 10 as best shown in Fig. 3. Extending from the same edge of the plate 10 from which the posts 14 project, are a plurality of tongues 15 spaced from but overlaying the plate 10 and parallel with the top face thereof, which has a plane surface.

Slidably mounted on the top of the fixed plate 10 is a movable plate 16 of substantially the same dimensions as the plate 10 and of a thickness to pass beneath the tongues 15. To ensure a close engagement of the plate 16 with the said tongues, I provide said plate with one

or more upwardly projected, rounded ribs 17 of a height to engage and flex the tongues 15 while the plate 16 is superimposed upon the plate 10 in a manner to be hereinafter described.

The outer edge of the plate 16 has a plurality of upwardly projecting, spaced arcuate posts 18, corresponding in number, spacing, height and form with the posts 14, with the portion adjacent the free end of each post projecting across, or transversely of, the plate 16 towards the end of a post 14. Each post 18 is complementary to a post 14 in forming a continuous loop when the plate is superimposed upon the plate 10 as shown in Fig. 1.

The construction of the plates 10 and 16 is such as to permit a free sliding of the latter upon the former, means being provided to ensure only a right line movement of the plate 16 and of its posts 18 in relation to the plate 10 and its posts 14, and to limit the amount of this movement and prevent the separation of the plate 16 from the plate 10.

To secure the above conditions in the binder shown in Figs. 1 to 3, I provide the plate 10 with upturned end flanges 19-20 and the plate 16 with upturned end flanges 21-22 having free sliding fit within the flanges 19-20 respectively. These flanges restrict the sliding movement of the plate 16 to a right line movement and prevent any substantial tilting or skewing of the plate 16 during such movement.

The end flanges 19-20 each carry a guide pin 23 passing through a slot 24 closed at each end, in the adjacent end flange 21 or 22. The arrangement permits free sliding of the plate 16, but limits the length of this movement and prevents a separation of the two plates due to excess movement of the plate 16.

While the right line movement of the movable plate 16 and its posts 18 in relation to the fixed plate 10 and its posts 14, ensures accurate, close, abutting relation of the ends of the complementary posts forming each loop, it is necessary to provide means preventing such movement of the plate 16 when the loops have been closed, as would permit even a slight separation of the ends of the posts. In Figs. 1 to 3 of the drawings, this means comprises locking plates 25 pivoted at one end near the top of each end flange 21 and 22 adjacent the outer edge of the plate 16 and having its free end formed into a looped or hooked member 26 adapted to pass over and embrace the top portion of the end flanges 21 and 22 adjacent the inner edge of the plate 16, and the top portion of the end flanges 19 and 20 adjacent the outer edge of the plate 10. The locking plate 25 has an outwardly projected finger piece 27, by means of which the locking plate may be moved about its pivot 28. The corners of the end flanges 19, 20, 21 and 22 engageable with the looped or hooked portion 26 should be rounded sufficiently to permit said looped end 26 to pass into engagement with the vertical edges of said flanges without developing unnecessary stresses tending to unduly flex the various posts 14 and 18. The inner top edges of the flanges 19-20 are cut away to afford clearance for the pivot 28.

In Fig. 5, there is shown a modified form of guiding, limiting and locking arrangement. The guiding means comprises a channel at each end of the fixed plate 10, formed by turning the end of the plate upon itself, as shown at 29. The ends of the movable plate 16 are slidably mounted in such channels. Each end of said plate 16 is

recessed as shown in dotted lines at 30, providing tongues 31 and 32, the tongue 31 being adapted by engagement with a stop pin 33, closing the channel adjacent one of its ends, to limit the outward sliding movement of the movable plate, and the tongue 32 affording support for a plate locking the movable plate against accidental movement. This locking plate 34 is pivoted adjacent a corner of the movable plate at the outer edge thereof. Two such locking plates are used, one adjacent each end of said plate 16. Said plate 34 is pivoted to the tongue 32 at 35. The free end of the plate 34 has a looped or hooked end 36, said plate being adapted to pass through a slot 33 in the bend of the plate 16 forming the channel 29 so that said looped or hooked end can pass and engage the turned portion of the plate 10 forming said channel 29. The locking plate 34 has an upwardly projected finger piece 37, by means of which it can be turned upon the pivot 35 to permit or to prevent sliding of the plate 16 to open or to close the loops formed by the posts 14 and 18.

The various parts of the binder may be formed from sheet metal or sheet plastics, or may be molded of plastic material. When sheet metal is used, a desired rigidity in the posts 14 and 18 may be secured by folding the side edges of the sheet metal in each post towards and upon the intermediate central portion, as shown at 39, Fig. 4, and at the bend of the metal at the juncture of the post with the plate carrying same, the edges of the turned portions may be outwardly flared as at 40, towards the plate to produce a substantially triangular area of a single thickness of metal. An indented portion 41 may be used to strengthen the post about the angle between the base of the post and the plate, which indentation extends into the adjacent portion of the plate.

The end of one of the posts forming a loop may be recessed as shown at 42 while the end of the complementary post co-operating therewith may have a projecting tongue 43 adapted to enter said recess to provide an overlap of the ends of the posts at the seam between their ends.

I have herein referred to the plate 10 as being a "fixed" plate and the plate 16 as being a "movable" plate. The words "fixed" and "movable" are used merely as a term of distinction, since while ordinarily only the plate 16 has a right line movement, it is possible under some conditions to open and close the binder loops by simultaneous, opposite movement of both plates 10 and 16, or even by movement of the plate 16 alone. This occurs when the loops are opened by pulling upon sheets collated upon the posts 14 and 18.

The operation of the herein described loose leaf binder is substantially as follows:

When it is desired to mount sheets in the binder, the locking plates 25 are turned upon the pivots 28 to disengage the looped end 26 thereon from the end flanges 19-20, 21-22, as shown in Figs. 2 and 3, or the looped end 36 from the plate 19 at the channel 29 as shown in Fig. 5. This permits a free sliding movement of the movable plate 16 upon and transversely of the fixed plate 10, the end flanges 19-20 and 21-22, or the channels 29, limiting this to a right line movement. Hence the ends of the posts move in a straight line away from their complementary posts (18 and 10) and there never is any such loss of alignment of such ends as will interfere with repeated, accurate engagements of such post

ends during succeeding openings and closings of the loops formed by such posts.

The movement of the plate 16 is limited by engagement of one end of the slot 24 with the stop pin 23, Figs. 1 to 3, or of the shoulder 31 with the pin 33, Fig. 5. During such movement, the plate 16 is in continuous engagement with the various tongues 15 which in addition to preventing upward or downward movement of the plate 16, holds papers collated upon the posts 14 out of engagement with the movable plate.

With the sliding of the plate 16 as described, the ends of all complementary posts 14 and 18 are separated, leaving a gap, Fig. 3, between the ends of such posts. The right line movement of the plate 16 ensures a gap of uniform width as to all post ends, Fig. 2. This ensures ample space between the ends of all complementary posts, for the insertion of one or a number of sheets therebetween and greatly facilitates the mounting, or the removal of sheets upon or from the posts upon either plate 10 or 16.

The facility with which sheets may be collated in a book having a binder embodying the invention, permits great economy in the production of such books, particularly when they are produced in large numbers in a bindery. Such binders are largely used in books wherein additional or replacement sheets or leaves are required to be placed by the user in the binder from time to time, as in catalogues, sample books, instruction sheets and the like.

After the required number of sheets has been mounted on either or both posts 14-18, it is merely necessary to slide the movable plate 16 in a right line across the fixed plate 10 until the free ends of all posts 18 simultaneously abut against the free ends of all posts 14. To keep the loops formed by complementary posts closed, it is merely necessary to swing the locking plates 25 or 34 about their pivots until the looped or hooked ends 26 or 36 engage the end flanges 19-20, on the rear edge of the plate 10, or about the channel portion 29. This movement of said pivotal locking plates draws the free ends of the posts 18 and 14 tightly together. If the posts flex slightly during this action, the amount of flexure will be so slight as not to be appreciable.

So long as the locking mechanism is set as described, the movable plate 16 is held against any sliding movement on the fixed plate 10 and any separation of the ends of the posts forming each loop upon a horizontal plane either transversely or longitudinally of the plates 10 and 16 is prevented. Furthermore, any separation of the ends of the posts vertically is prevented by the tongues 15 and the ribs 17 on the plate 16, since with the closing movement of the posts to form the loops, the plate 16 is forced and held against the plate 10 by the action of the ribs 17 and the tongues 15. The right line movement of the plate 16 results in the simultaneous engagement of said ribs with all tongues 15 and the continued engagement of these parts avoids any possibility of the ends of the posts getting out of vertical alignment during movement of the plate 16.

The essential characteristics of a binder embodying the invention are the two plates having arcuate posts as described which plates have a limited relative sliding movement in a right line to ensure accurate engagement of the ends of co-operating posts to close the binder and to provide a gap of uniform width between all posts upon one plate and those upon the other plate, when opening the binder; in conjunction with

means to prevent plate movement resulting in even slight separation of the ends of the posts while the binder is closed.

It is not my intention to limit the invention to the material used in the various parts of the binder, nor to the particular form of these parts shown in the drawing, it being apparent that such may be varied without departing from the spirit and scope of the invention.

Having described the invention, what I claim and desire to have protected by Letters Patent is:

A loose leaf binder comprising two plates, one movable with respect to the other solely by manual action applied directly thereto, one of said plates being a fixed plate and having a plurality of spaced arcuate posts projecting rigidly upwardly from one edge and transversely of said plate and an upwardly projected flange in each end of said plate, and the other of said plates being slidably mounted upon said fixed plate within limits and having a like number of complementary arcuate posts projecting rigidly upwardly from one edge and transversely of said plate towards the posts upon said fixed plate and adapted solely with inward right line movement of said slidable plate to have their ends engaged with the ends of the posts upon said fixed plate to form a series of closed loops, said engagement occurring only at the inward limit of sliding motion, an upwardly projected flange at each end of said slidable plate having a sliding fit with the

flanges on said fixed plate, a slot and pin connection between the flanges at each end of said plates whereby a limited right line movement thereof is permitted, and a locking plate pivoted upon one flange having a looped end adapted to be manually engaged with or disengaged from the cooperating flange upon the other plate only when the posts are engaged, whereby movement of said slidable plate when the posts are engaged is prevented.

ATTO N. HANNA.
